FIG. 1 is a perspective view of a confection, showing a first embodiment of our new design;

FIG. 2 is a side elevation view of the embodiment shown in FIG. 1;

FIG. 3 is another side elevation view of the embodiment shown in FIG. 1;

FIG. 4 is a front elevation view of the embodiment shown in FIG. 1;

CLAIM

We claim, the ornamental design for a confection, as shown and described.

DESCRIPTION

FIG. 5 is a rear elevation view of the embodiment shown in FIG. 1;
FIG. 6 is top plan view of the embodiment shown in FIG. 1;
FIG. 7 is a bottom plan view of the embodiment shown in FIG. 1;
FIG. 8 is a perspective view of a confection, showing a second embodiment of our new design;
FIG. 9 is a side elevation view of the embodiment shown in FIG. 8;
FIG. 10 is another side elevation view of the embodiment shown in FIG. 8;
FIG. 11 is a front elevation view of the embodiment shown in FIG. 8;
FIG. 12 is a rear elevation view of the embodiment shown in FIG. 8;
FIG. 13 is a top plan view of the embodiment shown in FIG. 8;
FIG. 14 is a bottom plan view of the embodiment shown in FIG. 8;
FIG. 15 is a perspective view of a confection, showing a third embodiment of our new design;

FIG. 16 is a side elevation view of the embodiment shown in FIG. 15;
FIG. 17 is another side elevation view of the embodiment shown in FIG. 15;
FIG. 18 is a front elevation view of the embodiment shown in FIG. 15;
FIG. 19 is a rear elevation view of the embodiment shown in FIG. 15;
FIG. 20 is a top plan view of the embodiment shown in FIG. 15; and,
FIG. 21 is a bottom plan view of the embodiment shown in FIG. 15.
The evenly-spaced broken lines in FIGS. 8-21 illustrate portions of the confection that form no part of the claimed design. The dash-dot-dash broken lines shown in FIGS. 15-17 and 20-21 illustrate the boundary of the claimed design that forms no part thereof.
The dash-dot lines are boundary lines delimiting claimed from unclaimed subject matter.
